UNITED STATES PATENT OFFICE.

AMELIA CORYELL, OF DENVER, COLORADO.

TOILET-ARTICLE CASE.

1,420,523.

Specification of Letters Patent. Patented June 20, 1922.

Application filed March 8, 1920. Serial No. 364,006.

To all whom it may concern:

Be it known that I, AMELIA CORYELL, a citizen of the United States, residing at Denver, in the county of Denver and State 5 of Colorado, have invented new and useful Improvements in Toilet-Article Cases, of which the following is a specification.

This invention relates to a combination toilet article and the principal object of the 10 invention is to provide a case containing a set of manicuring articles which are pivotally mounted therein so that the articles may be used without detaching them from the case.

Another object of the invention is to provide means for detachably mounting a pair 15 of scissors in said case so that the scissors may be detached from the case when desired.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying 30 drawings wherein like characters denote like or corresponding parts throughout the several views, and in which:—

Figure 1 is a view of the case in folded condition.

Figure 2 is a view with the case in open condition.

Figure 3 is a view of the scissors.

In these views A indicates the case which is formed of the two portions 1 and 2 which are hinged together as at 3. 4 indicates a fastener for holding the case in closed condition. At one end of one part of the case is a small stud 5 which is adapted to be engaged by a hook 6 on one of the handle portions of the scissors 7 so that said scissors are hingedly mounted in the case and may be 45 detached therefrom by raising the hook off the stud. The other handle part of the scis-

sors is formed of two portions hinged together at 8 so that this handle part may be folded so that the scissors may lie within the case. A file 9, a knife 10 and the tweezers 50 11 are also pivotally mounted in the case so that they may be swung outwardly when they are to be used. When not in use they are swung inwardly so as to lie within the case and will be enclosed by said case when 55 the same is in closed position.

It will thus be seen that all of the articles are attached to the case so that there is no danger of mislaying the articles after use, and the entire device may be carried about 60 without the articles cutting the pocket-book or vanity case or becoming entangled with other articles therein.

It is thought from the foregoing description that the advantages and novel features 65 of my invention will be readily apparent.

I desire it to be understood that I may make changes in the construction and in the combination and arrangement of the several parts, provided that such changes fall within 70 the scope of the appended claims.

What I claim is:—

1. A device of the class described comprising a foldable case, a pair of scissors one handle of which is hingedly and detachably 75 connected with said case, the other handle part of said scissors being formed of two portions hinged together.

2. A device of the class described comprising a foldable case, a set of manicuring instruments having the ends of their handle portions pivotally connected with said case and a pair of scissors having a hook at the end of one of the handle portions, a stud in said case for engaging said hook, the other 80 handle portion of the scissors being formed of two sections which are hinged together and means for holding the case in closed condition.

In testimony whereof I affix my signature. 90

AMELIA CORYELL.
